(57) **CLAIM**

The ornamental design for a mop head, as shown and described.

DESCRIPTION

FIG. 1 is a front, top and right-side perspective view of a mop head showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a back, bottom and left-side perspective view thereof; and,

FIG. 9 is another perspective view showing the mop head in use.

The broken lines in FIG. 9 depicting mop strings represents environmental subject matter that forms no part of the claimed design.

The broken lines throughout the figures depict portions of the mop head that form no part of the claimed design.
